INTERNAL COMBUSTION ENGINES

Alfons Hilpert, Hamburg-Blankenese, Germany

Application July 22, 1950, Serial No. 175,338

1 Claim. (Cl. 123—32)

This invention relates to internal combustion engines. The object of the present invention is to effect a shortening of the period of combustion or to obtain a more rapid and sudden rise of pressure in internal combustion engines of all kinds whether they use solid, liquid or gaseous fuels. This result is obtained, in accordance with the invention, by producing a jet of flame having a velocity between 80 metres per second and the velocity of sound or above this which increases the velocity of combustion in the chamber above the piston up to the velocity of the jet. The production of the jet of flame can be effected by causing a mixture of fuel and air to be brought to combustion by means of a sparking plug or other ignition devices with increase of temperature and pressure in a relatively small auxiliary chamber which is in communication with the compression chamber of the cylinder through small openings or passages, so that, owing to the increased pressure produced, the combustion gases are forced into the compression chamber through the small openings in the form of jets of flame having a high velocity which in some cases may be as great as the

velocity of sound. The velocity of the jet of flame can be increased in stages by arranging two or more auxiliary or side chambers in series, for example, in such a manner that an increase in pressure due to combustion takes place in the first chamber by ordinary ignition, and the pressure is increased further in the second chamber and so on up to the combustion chamber of the cylinder, in such a manner that a jet of flame passing through suitably dimensioned openings with accelerated velocity causes the speed of combustion to increase from chamber to chamber. A further increase in the effect aimed at can also be obtained by producing a number of jets of flame directed towards one another which, by impinging on the gas above the movable piston effects its combustion or detonation.

Since the combustion produced by the jet of flame takes place on the one hand in the direction of movement and with the velocity of the flame, and on the other hand also proceeds in all directions with the normal velocity of about 80 metres per second, the total combustion velocity is equal to the resultant of the two. The increase in the rate of pressure increase produces a dynamic pressure which is manifested mainly in an increase in pressure and temperature and in an elastic blow on the piston, this effect being the more noticeable the more quickly combustion takes place.

The means for carrying the method of the invention into effect may be divided into those for use with existing two-stroke and four-stroke cycle engines and those for new constructions. In the case of existing engines the necessary additional devices comprising the auxiliary chamber, or chambers, can be adapted to suit the form of the combustion chamber and the requirements of the invention, whereas in the case of new constructions the form or design of the combustion chamber can be adapted to suit the requirements of the invention.

2

In all the cases, the advantage of an economy of fuel or an increase in the power of the internal combustion engine is obtained.

5 A device suitable for carrying out the method of the invention is illustrated, by way of example, in the accompanying drawings; in which:

Figure 1 is a complete vertical section through the central axis of the cylinder at right angles to the crank shaft of an upright two-stroke cycle engine with a valve 10 between the auxiliary chamber and the main combustion chamber, for obtaining different degrees of compression in the two chambers and for effecting ignition in the auxiliary chamber.

Fig. 2 is a section through the wall separating the two combustion chambers.

Fig. 3 illustrates a perforated plate, the openings of which may be closed by a controlled valve located between the main chamber and the auxiliary chamber.

Figure 1 shows a complete vertical section through the central axis of the cylinder at right angles to the crank shaft of an upright two-stroke cycle engine having a controlled valve 49 between the main chamber 47 and the auxiliary combustion chamber 46, for obtaining different degrees of compression in the two chambers, for enabling self-ignition to take place in the chamber 47.

The two chambers are separated by the valve 49 and a wall 50. Also separate water cooling can be provided for the partition between the two chambers and the bottom but this may be dispensed with. The injection of fuel is effected from above through the high pressure nozzle 48 which produces a jet directed towards the left into the closed combustion chamber 46 in which the compression pressure is about 20 atmospheres and also produces a jet directed towards the right into the chamber 47 where a compression pressure of about 35 atmospheres is produced in order to effect self-ignition. During compression the control valve 49 remains open until a pressure of about 20 atmospheres is reached whereupon the valve is positively closed and the remainder of the compression stroke increases the pressure only in the chamber 47 up to about 35 atmospheres. During the injection of the fuel into both chambers which takes place at the upper dead point or shortly before this is reached, only an atomised mixture is produced in the combustion chamber 46 because the pressure and temperature are not sufficient for self-ignition, whereas in the chamber 47 self-ignition occurs as in diesel engines at a compression pressure of about 35 atmospheres. The valve 49 is held closed up to this moment and is then positively opened. During the equalisation of pressure which then occurs through the valve port, a maximum pressure of about 60 atmospheres in the chamber 47 is opposed to a pressure of about 20 atmospheres in the combustion chamber 46, so that, on discharge a jet of flame having the speed of sound is produced, and the pressure at the orifice is the so-called critical pressure which amounts to about the half, i. e. to about 30 atmospheres. Therefore, the jet of flame will spread out to all sides in the auxiliary combustion chamber with maximum velocity and the dynamic pressure increase to a maximum and be converted into heat. The

60 valve 49 may in some cases open and close a number of openings 51 as indicated in Figures 2 and 3. Any suitable means may be used to close the valve 49, while the spring 52 holds it open.

65 I claim:

An internal combustion engine having an auxiliary chamber and a main combustion chamber, a common high pressure fuel injection nozzle for the main combustion chamber and the auxiliary chamber, an opening between the main combustion chamber and the auxiliary chamber, a valve in the main combustion chamber for closing the opening between the main combustion cham-

ber and the auxiliary chamber, and means actuating said valve for closing said opening when a predetermined compression pressure is reached, said valve being positively opened after self-ignition of the fuel-air mixture in the main combustion chamber.
